F. D. PILLE
ELECTRICAL CONNECTER
Filed April 5, 1919

INVENTOR
F. D. PILLE

BY
J. J. Mallanui
ATTORNEY

UNITED STATES PATENT OFFICE.

FREDERICK D. PILLE, OF DENVER, COLORADO.

ELECTRICAL CONNECTER.

Application filed April 5, 1919. Serial No. 287,863.

To all whom it may concern:

Be it known that I, FREDERICK D. PILLE, a citizen of the United States, residing at Denver, in the county of Denver and State 5 of Colorado, have invented certain new and useful Improvements in Electrical Connecters, of which the following is a specification.

This invention relates to electrical connectors of the type used in making connections between the terminals of two or more batteries for the purpose of effecting a current flow between them.

The primary object of the invention is to provide a device of this character which is composed of a continuous piece of spring wire or other suitable material and which provides two cooperative jaws to clampingly engage the terminal or other electrical device to which the connector is applied.

By making the connector of a continuous piece of metal the two jaws are always in circuit and insulation of any part of the article by corrosion is prevented.

Another object of the invention is to provide a connector of the type mentioned which by the extreme simplicity of its construction combines strength and durability with low cost of production.

With these and other objects in view, all of which will fully appear in the course of the following description, my invention consists in the novel constructions and combinations of parts shown in the accompanying drawings in the various views of which like views are similarly designated and in which—

Figure 1 is a plan view of the improved connector in its preferred form,

Figure 2, a fragmentary section on the line 2—2, Figure 1.

Figure 3, a section taken along the line 3—3, Figure 2,

Figure 4, an enlarged section on the line 4—4, Figure 1,

Figure 5, an enlarged section taken on the line 5—5, Figure 1,

Figure 6, a plan view of two connectors of the improved construction connected for application to the terminals of two batteries, and

Figure 7, a plan view of a modified form of the invention.

The connector as shown in Figures 1 to 6 of the drawings consists of a single piece of wire doubled and bent to provide coopera-

tive jaws 2 at the ends of substantially aligned shanks 3 formed of laterally extending parts of convergent members 4 which at their lapping ends are bent into eyes 5 for 60 their connection by a coupling-bolt 6.

The shanks cross each other adjacent their ends at which the jaws are formed and a spring-loop 7 between the members adjacent their connected ends, holds the jaws 65 yielding together.

In order to form the entire clamp of one continuous piece, the wire is doubled, its central portion is coiled to form the spring loop 7 and its doubled portions at opposite 70 sides thereof are bent to form the spring-legs 8, the shanks 3, the jaws 2 and the members 4.

The jaws are preferably made by bending the doubled wire into triangular form as 75 shown in Figures 2 and 4 of the drawings and they are covered by plates 9 which are bent around their sides and which at their edges corresponding with the ends of the jaws, are bent and serrated to provide teeth 80 10 which bite into the terminal or other object placed between the jaws and thus assure their firm and conductive connection therewith.

This clamp is in practice fastened at the 85 end of a conductor of electricity by a clasp 13 which is attached to the bolt 6.

The clasp consists of a strip of metal having an eye 14 for its connection with the bolt and one or more pairs of opposite 90 pliable wings 15 which are bent around the conductor as clearly shown in Figure 1 of the drawings.

In order to assure a flow of current to both the jaws of the clamp and prevent 95 their insulation by corrosion at the connected ends of the wire of which the device is composed, the ends are welded together as shown at 16 in Figure 2.

After the parts of which the connector is 100 composed are formed and assembled as hereinbefore described, the entire article is electrically lead-coated as a protection against the corrosive activity of the acids commonly used in batteries of the type to which my invention is most frequently applied.

In the modified construction illustrated in Figure 7 the end portions of the wires instead of being joined at their extremities, are wound around the convergent legs 8 of 110 the spring loop 7.

The connector is attached to the conduc-

- tor of electricity by placing an end thereof between one of the legs of the spring and the convolutions 17 of the end portion of the wire wound around the same.
5. The method of using the connectors is too well-known to those skilled in the art to require further explanation at this point, it being obvious that a pair of connected clamps made in accordance with my invention may be employed to advantage in charging batteries, testing telephone wires and other electrical conductors and in making temporary repairs in a broken circuit without the use of special tools.
10. In Figure 6 of the drawings are shown two of the connectors attached at opposite ends of a conductor of electricity and in clamping engagement with the terminals 18 of batteries 19.
15. Although I have shown but two different forms of my invention in the present application I know that it is possible to make other modifications too numerous for separate illustration, and I desire it understood that such modifications may be availed of within the spirit of my invention as set forth in the following claims:
1. An electrical connector composed of a continuous piece of doubled wire the middle portion of which is looped to provide a spring, and which is bent to form convergent legs at opposite sides of the loop, members extending along said legs and joined at one of their ends, and jaws composed of the portions of the wire between said legs and said members.
2. An electrical connector composed of a continuous piece of doubled wire the middle portion of which is looped to provide a spring, and which is bent to form convergent legs at opposite sides of the loop, members extending along said legs and joined at one of their ends, jaws composed of the portions
30. of the wire between said legs and said members, and a bolt connecting the joined ends of the legs.
3. An electrical connector composed of a continuous piece of doubled wire the middle portion of which is looped to provide a spring and which is bent to form convergent legs at opposite sides of the loop, members extending along said legs and joined at one of their ends, jaws composed of the portions of the wire between said legs and said members, a bolt connecting the joined ends of the legs, and a fastening for a conductor of electricity connected to the bolt.
4. An electrical connector composed of a continuous piece of doubled wire the middle portion of which is looped to provide a spring and which is bent to form convergent legs at opposite sides of the loop, members extending along said legs and welded together at one of their ends, and jaws composed of the portions of the wire between said legs and said members.
5. An electrical connector composed of a continuous piece of doubled wire the middle portion of which is looped to provide a spring and which is bent to form convergent legs at opposite sides of the loop, members extending along said legs, and fastened at their ends, and jaws composed of the portions of the wire between said legs and said members.
6. An electrical connector composed of a continuous piece of doubled wire the middle portion of which is looped to provide a spring, and which is bent to form convergent legs at opposite sides of the loop, members extending along said legs, and jaws composed of the portions of the wire between said legs and said members.

In testimony whereof I have affixed my signature.

FREDERICK D. PILLE.
